CLAIM

The ornamental design for a nail clipper as shown and described.

DESCRIPTION

FIG. 1 is a top perspective view of a nail clipper, showing my new design;

FIG. 2 is a front view of the nail clipper of FIG. 1;

FIG. 3 is a rear view of the nail clipper of FIG. 1;

FIG. 4 is a right side view of the nail clipper of FIG. 1;

FIG. 5 is a left side view of the nail clipper of FIG. 1;

FIG. 6 is a top view of the nail clipper of FIG. 1;

FIG. 7 is a bottom view of the nail clipper of FIG. 1; and,

FIG. 8 is bottom perspective view of the nail clipper of FIG. 1.

The broken lines illustrate portions of the nail clipper that form no part of the claimed design.
